CABLE FITTING

William L. Rochester, Jr., Warrenton, Va., assignor to
Rochester Ropes, Inc.

Filed May 19, 1958, Ser. No. 736,070

4 Claims. (Cl. 287—78)

This invention relates to terminal type fittings for use with strand, flexible cable, wire rope and the like.

Wherever wire cable is used, there is a necessity for attaching a fitting of some kind, either at the ends of the cable or at an intermediate point on the cable. Better methods of applying fittings have been the goal of workers in this art for many years, but they have only developed a limited number of successful styles, for example: (1) wire rope sockets applied with molten zinc, (2) hand splices, (3) swagings, (4) pressed-on fittings, and (5) wire rope clips and clamps.

These prior art types of fittings require very expensive and bulky machinery to apply, a high degree of manual skill, or they do not develop sufficient efficiency for the degree of effort required. The prior art wire rope sockets develop, when properly applied, 100 percent of the breaking strength of the cable. The factors involved in correct application are correct temperature of molten zinc, purity of zinc, chemical cleanliness of the open and brushed end of the cable to which it is to be applied, and correct alignment of the socket on the wire rope prior to zinc being poured. The cost of labor and materials for this fitting is quite high, labor and materials exceeding the cost of the actual fitting itself.

The hand splice on cable requires a high degree of manual skill and strength, in addition to the splicing tools which, although not expensive, are bulky and not portable. A correctly applied hand splice cannot be trusted to exceed 75 percent of the breaking strength of the cable used.

Workers in the prior art have discovered that swaging produces a fitting which often is stronger than the cable itself. Other workers have found that some fittings could be applied by hand tools which were quite satisfactory up to a certain strength, but were not of the neat and smooth appearance of the usual machine-applied swage-type. Appearance as well as strength, of course, is of vital importance around consumer viewed fittings such as those found in yachts and airplanes. Swaged fittings involve an expensive, very accurate machined fitting, applied usually by means of a rotary swaging machine which is both non-portable and very expensive, and a high degree of skill in the operator of the machine applying this fitting. The cost of machinery to apply fittings to rope in excess of $\frac{1}{2}$ " in diameter is extremely high because of the power needed and the size of the machinery used. This fitting will develop 100 percent of the breaking strength of the rope.

Clips and clamps, although inexpensive, are unsatisfactory wherever appearance and strength are paramount.

One prior art method of applying fittings has involved the use of an inner metal core tapered to conform with a tapered inner surface of an outer sleeve. Such prior art fittings provide some degree of grip on the cable member, but they all require an unreasonable amount of power to be applied to grip sufficiently to approach the breaking strength of the cable. This excess power which must be applied normally distorts the designed shape of the cable which materially reduces the actual strength thereof.

One object of the invention described herein is to provide fittings for cables which may be applied without

2

the use of expensive machinery with the application of a minimum amount of power, without highly skilled operators, and which fittings normally will develop at least 100 percent of the design strength of the cable to which applied.

5 These and other objects of the invention will be readily understood by reference to the following description and accompanying drawings, in which:

Fig. 1 is a longitudinal exploded view of one embodiment of the invention shown partly in section;

10 Fig. 2 is a sectional view of the embodiment of Fig. 1, with the parts assembled;

Fig. 3 is an end view of one unit of the sleeve section shown in Fig. 1;

Fig. 4 is a section taken along the line 4—4 of Fig. 1;

15 Fig. 5 is a section taken along the line 5—5 of Fig. 2 showing the sleeve cold flowed on the cable;

Fig. 6 is a perspective view showing a further embodiment of the present invention, showing a one-half portion of a malleable sleeve section;

20 Fig. 7 is a close-up view of a conventional cable;

Fig. 8 is a view similar to Fig. 4 with an elliptical figure imposed therein to facilitate further description of the invention;

25 Fig. 9 is a plan view showing a further embodiment of the invention.

The first embodiment of this invention described below accomplishes all of the objects and advantages of a machine swaged fitting through the use of a structure generally comprising a malleable sleeve pre-shaped internally to be fitted onto a portion of the cable and pre-shaped externally to generally repeat the internal configuration, a compression member to surround the malleable sleeve, and a terminal piece connected to the compression member through the use of a thread arrangement by which

30 tightening of the terminal connector to the compression member will result in the malleable sleeve being cold flowed into the interstices of the wire cable.

Referring now to Fig. 1 of the drawings, 10 indicates a complete fitting adapted to be placed on the end of cable

35 20. A malleable sleeve, generally designated as 30 in the embodiment shown, is made of a series of rings 31. Referring to Fig. 3, it can be seen that the interior surface

39 and the exterior surface 33 of each of said rings generally approximates the lay of the cable; i.e., the configuration of the cable 20, which generally comprises, as

40 shown in Figs. 4 and 5, six outer strands 21 and an axial strand 22. Each strand, as shown in Fig. 7, is composed of a series of wires 23.

45 In the form shown in Fig. 7, the wires 23 are set with a reverse twist relative to that of the strands 21. The strands 21 form lands 24 along

50 their outer surfaces and form grooves 25 along their adjoining surfaces.

The malleable sleeve sections 31, as shown particularly in Figs. 1, 3 and 4, are provided internally with lands 34

55 and grooves 35 generally mating with the lands 24 and grooves 25 of the cable 20. The sleeve sections 31 are provided externally with lands 36 and grooves 37 which

generally repeat the interior lands and grooves 34 and 35. The sections 31, in one form, taper or decrease progressively in diameter, away from the end of the cable, as

60 in Fig. 1.

While the exterior surfaces of the malleable sleeve 30 in preferred form is shown in tapered form having a taper slightly greater than the taper of the internal surface 41 of the outer compression member 40, it will be

65 apparent that the present invention is not limited to the provision of a taper on the exterior surface of the sleeve 30. In the event a taper is employed, it is preferable to construct the taper sufficiently low pitched to prevent action thereof as a shoulder through friction, particularly in such construction, as shown in Fig. 1, where the

70

internal surface area 42 is first contacted by the most remote portion 32 comprising the largest tapered portion 32 of the malleable sleeve 30.

After the rings 31 have been properly arranged according to taper on the cable 20, the compression member 40 is slipped over the sleeve. The member 40 has an interior portion threaded at 43, and another interior portion tapered at 41. This taper 41 can be the same as the taper 36 of sleeve 30, or it can be less than the taper of the sleeve 30, as represented by the line 36. The rings 31 progressively decrease in outside diameter, so that their resultant taper, represented by line 36, is the same as or less than the taper 41 of the member 40.

To complete the fitting, a terminal connector 50 is provided, consisting of an abutment portion 51, a threaded portion 52 and an anchorage hook or eye portion 53.

The interior cross sectional diameter at point 42 of the member 40 is slightly less than the maximum outside diameter of the most remote and maximum diameter portion 32 of the malleable sleeve 30. As the member 40 is moved toward the sleeve 30 in Fig. 1, the ring 31 will act as an abutment. The terminal connector 50 is then threaded into member 40 at 43. The connector is rotated to force taper 41 into progressive abutment with portion 31. By virtue of the present construction, the malleable sleeve 30 is finally collapsed and cold flowed in and about the cable 20. As the threading continues, preceding portions of the core come into progressive abutting contact with taper 41 of the member 40 until the entire sleeve is collapsed and the metal cold flowed into the interstices of the cable.

It will be noted that due to the difference in tapers of 41 and 36, there is a point by point circumferential contact made along the entire malleable sleeve. This point by point application of pressure taken in conjunction with the high mechanical advantages gained through the use of the threads or the like, cold flows the sleeve into the interstices of the cable. Fig. 2 shows the sleeve completely cold flowed, and Fig. 5 is an enlarged cross sectional view thereof showing the sleeve metal cold flowed into the interstices of the cable.

Despite the tremendous pressures concentrated through the point by point application of power, and developed by the mechanical advantage of screw threads, the present construction provides further assurance of obtaining maximum strength. This further assurance becomes increasingly important as the diameter of the cable becomes greater.

One law of mechanics which is to be accounted for in applying this type fitting can best be expressed by the visualization of a walled cylinder whose cross sectional shape is a perfect circle. When an equal force is applied to all points along the exterior circumference of this cylinder directly toward the center, this force is transferred from a force toward the center to a compressive force within the wall of the cylinder. Metal being relatively incompressible, a cylinder of this type builds up a very high resistance to being compressed, collapsed or swaged.

One reason the prior art has never reached the degree of strength sought apparently is because the shape of the malleable portion either is, or becomes, a cylindrical tube prior to the filling of the cable portion between the strands. This may be expressed by the mathematical phenomenon described symbolically in A. E. H. Love's formula (Mark's Handbook—McGraw-Hill Book Company, Third Edition, page 433):

$$p = (2E/1-m^2) \times (t/d)^3 \text{ for thin tubes}$$

where

P =collapsing pressure, p.s.i.

t =thickness of tube, in inches

D =outside diameter of tube, in inches

E =modulus of elasticity

m =Poisson's ratio (see page 412 of Mark's Handbook)

On page 433 of the Handbook there is also given a correction factor for ellipticity and variations in thickness. The correction factor demonstrates the dramatic reduction in force necessary to collapse a tube which departs from true circular shape. This correction factor (C) can be expressed as: $C = (D_{\min}/D_{\max})^3(t_{\min}/t_{\max})^3$. When considering this correction factor, Love's formula become $P = [2CE/1-m^2](t/D)^3$ for thin tubes, where t =average thickness, and D is diameter in inches.

10 A simple application of these formulae indicates the mode of operation of the present invention. Assume for the purposes of the problem that it is intended to compress a brass core of $\frac{1}{16}$ " thickness and having an outside diameter of $\frac{5}{8}$ ". For brass tubes $E=14,000,000$ and $m=1.357$, therefore collapsing pressure

$$(P) = \frac{2(14,000,000)}{[1 - (.357)^2]} \times \frac{(\frac{1}{16})^3}{(\frac{5}{8})}$$

or $P=32,090$ pounds per inch², and is the amount of pressure necessary to collapse the tube.

20 Referring now to Fig. 8 which is a cross section through the cable and sleeve of this invention, it can be seen that at any one cross section, this fitting will function to collapse as three non-circular tubes, one of which is designated at 60. For illustrative purposes, again using brass as the metal of the core, and applying the correction factor for elliptical design and variations in thickness:

$$t = \frac{1}{16}$$

$$D_{\max} = \text{largest outer diameter} = \frac{5}{8}$$

$$D_{\min} = \text{smallest outer diameter} = .292$$

$$\text{Correction factor} = (D_{\min}/D_{\max})^3 \times (T_{\min}/T_{\max})^3$$

$$= \frac{(.292)^3}{(.625)} \times \frac{(.0625)^3}{(.0625)}$$

$$= (.466)^3 \times 1$$

$$C = .102$$

therefore the collapsing pressure necessary to collapse the fitting as designed will be

$$P = .102 \times 32,090$$

$$= 3,270 \text{ p.s.i.}$$

45 It will be noted that each non-circular element will have a tendency to compress, or collapse at almost $\frac{1}{16}$ " the pressure necessary to compress or collapse a true tubular element. It is desired to point out that the invention is not to be restricted to any particular theory, such as that propounded above, the advantages being obtained by the novel structure of the present invention.

50 The phenomenon expressed in the above formulae appear to be related to the fitting combination herein described. In breaking up the tubular sleeve into a series of non-circular sleeves, the entire sleeve will have a greater tendency to collapse. The shape of the sleeve must be such that a circular tube will not be created prior to the cold flowing of sufficient metal into the interstices of the cable.

55 Another advantage of the configuration can be seen in Fig. 8. When a pressure P is applied at a point on the land 33 of the sleeve 30, forces P' and P'' are applied in a non-concentric direction which provides for improved multi-directional cold flowing of the malleable sleeve metal.

60 Having the inner and outer surfaces of the sleeve generally conform to the surface of the cable, has the additional advantage of requiring the metal to be cold flowed only a short distance before reaching the interstices of the cable; i.e., the sleeve metal is already pre-formed into the grooves 25.

65 In the preferred construction, and referring to Fig. 8, a circle 61 struck about the dual axis, O , of the cable and sleeve, which circle is tangent to the points 35a on the inner surfaces 35 farthest from center O , will also pass through the bottoms 37a of the outer grooves 37. Such geometrical accuracy, while preferred, is illus-

trative rather than restrictive of the invention; so that circle 61 passes only approximately through points 37a and 35a. This avoids the difficulty of compressing or deforming a cylinder.

A further embodiment of the malleable sleeve 30 is shown in Fig. 6 where the sleeve 70 is cast into two longitudinally separated pieces each of which is of the shape shown in Fig. 6. The interior surface 71 has the general shape of the cable 20 and the exterior surface 72 likewise has a general configuration like the cable 20, and in addition, preferably has a taper 73 similar to taper 36 in the embodiment of Fig. 1.

Fig. 9 shows a further embodiment, the fitting being in the form of a sleeve having a cable-shaped exterior 81 and a cable-shaped interior 82. The fitting has an integral terminal connector anchorage portion 83. This embodiment has the further advantage that it may be cold flowed onto a cable by means of a conventional press or swaging machine of very low power rate. The fitting 80 in effect serves the same purpose as the malleable sleeve in the embodiment of Fig. 1 with a connector portion already attached.

Referring now to Fig. 7, disclosing a conventional wire cable 20, the primary strands 21 are shown twisted in one direction, while the wires 23, making up each primary strand, are twisted in an opposite direction. Thus, it will be apparent that when fittings of the present construction are cold flowed into the interstices of the cable, a resistance to rotation in either direction is created. Also, it will be apparent that the resistance the fitting has to slipping off the cable is, in effect, equal to the total cross-sectional shear resistance of the metal cold flowed into the interstices. The holding principle involved in this invention is not primarily one of friction but rather one of shear resistance.

In a general manner, while there has been disclosed in the above description, what are deemed to be the most practical and efficient embodiments of the invention, it will be understood that the invention is not limited to such embodiments as changes may be made in the arrangement, disposition and form of the parts without departing from the principle of the present invention as comprehended within the spirit and scope of the accompanying claims.

I claim as my invention:

1. A fitting for a cable comprising in combination, a malleable sleeve and a compression member, said sleeve adapted to fit between a portion of said compression member and said cable, the exterior surface of the sleeve and the interior surface of said compression member being in contact at one point and being progressively further out of contact along their length toward the end opposite said point of contact, said compression member having an interior threaded section, a threaded terminal anchorage member adapted to mate with said threaded section whereby said malleable sleeve will be compressed progressively as said anchorage member is tightened into said compression member.

2. A malleable sleeve adapted to be cold flowed onto a wire cable of the type having lands and grooves on the surface thereof along its length and throughout its cross-section, said sleeve having on its interior and exterior surfaces lands and grooves generally conforming to the configuration of the lands and grooves of said wire cable, wherein a circle about the axis of the sleeve as a center, and having a radius passing substantially through the bottoms of the several exterior grooves is also substantially tangent to the interior grooves at points farthest removed from said center.

3. The sleeve as defined in claim 2 wherein said exterior surface has a taper throughout the longitudinal length of said sleeve.

4. The fitting as described in claim 1 wherein said malleable sleeve has on its interior and exterior surfaces lands and grooves generally conforming to the configuration of the lands and grooves of said cable.
